UNITED STATES PATENT OFFICE.

LOUIS W. SOUTHGATE, OF WORCESTER, MASSACHUSETTS, ASSIGNOR TO CHARLES KOHLER, OF NEW YORK, N. Y.; VERONICA M. KOHLER, WILLIAM B. ELLISON, AND RICHARD W. LAWRENCE, OF NEW YORK, N. Y., EXECUTORS OF SAID CHARLES KOHLER, DECEASED.

UPRIGHT AUTOMATIC PLAYER-PIANO.

1,118,958.

Specification of Letters Patent.

Patented Dec. 1, 1914.

Application filed October 9, 1911. Serial No. 653,560.

To all whom it may concern:

Be it known that I, Louis W. Southgate, a citizen of the United States, residing at Worcester, in the county of Worcester and 5 State of Massachusetts, have invented a new and useful Upright Automatic Player-Piano, of which the following is a specification.

The object of this invention is to provide 10 a new and improved upright automatic player piano which, while containing a full set of strings, actions and operating devices therefor, will be of small width relatively to the ordinary piano or player piano. To 15 this end, I arrange the set of strings in sections in different vertical planes and I divide the actions into sections arranged out of line with each other and substantially within the same width, and provide operating devices therefor. By arranging the 20 strings in two vertical planes and by dividing the actions into two sections and by providing automatic operating devices therefor, I am enabled to make a player piano of substantially 25 half the width of an ordinary player piano and of very little, if any, extra depth or height as compared with the ordinary player piano.

The invention is preferably applied so as 30 to produce a keyless instrument or one which is operated only automatically. An instrument of this character will fill a long felt want for those who desire to keep their original expensive pianos, such as grands, etc., 35 and who desire at the same time to have a player piano which will have a set of strings the same in number as the ordinary piano and which instrument can be conveniently placed on account of its small size. The 40 instrument is also adapted for use in flats, apartments, railroad cars, on ships and in other locations where space is an important factor. By providing a player piano which will play a full set of strings of practically 45 half size or width, as compared with the ordinary player pianos, the above felt want can be satisfied. The instrument also can be conveniently moved about because it is of much less weight than an ordinary player 50 piano. The instrument also is adapted to extend the field of the ordinary player piano by reason of its small cost.

The invention may be developed in sev-

eral forms, several of which are shown in the accompanying seven sheets of drawings 55 forming part of this application for patent.

Referring to the drawings and in detail, Figure 1 is a front elevation of a player piano constructed to embody my invention. Fig. 2 is a cross sectional elevation thereof. 60 Fig. 3 is a partial front sectional elevation illustrating the relative arrangement of tracker mechanism and motor used in the instrument shown in Figs. 1 and 2. Fig. 4 is an enlarged sectional view through the 65 operating pneumatics and valves therefor. Fig. 5 is a view similar to Fig. 2 illustrating a modified arrangement of parts to embody the invention. Fig. 5^a is a partial view 70 similar to Fig. 5 illustrating a modified arrangement of string frame which can be employed in the instrument shown in Fig. 5. Fig. 6 is a view similar to Fig. 2 illustrating a further modified arrangement of parts which may be employed in practising the 75 invention. Fig. 6^a is a partial view similar to Fig. 6 illustrating a modified arrangement of string frame which may be employed in the instrument shown in Fig. 6, and Fig. 7 is another view similar to Fig. 2 80 illustrating a still further modified arrangement which may be used for practising the invention.

Referring to the drawings and in detail and first to the instrument shown in the first 85 four sheets of the drawings, A designates a piano casing made of substantially half the width of the casing of an ordinary piano. This casing is superposed on a frame designed to contain and support the various 90 instrumentalities.

B designates the main string frame which in the construction under consideration is made to carry part of the set of strings and preferably the longer or bass section E of 95 the strings, which can be arranged vertically or inclined and overstrung as in the ordinary piano. This string frame is arranged on beams C at the rear of the piano. D designates the sounding board which is carried by said beams and with which the section E of the strings cooperates by means 100 of the usual bridges F.

B' designates a supplemental string frame which preferably is arranged to carry the 105 shorter or treble section E' of the strings.

This supplemental string frame B' is supported by beams C', between which is arranged a supplemental sounding board D', so that the treble strings E' can co-act therewith by means of the usual bridge or bridges F'. This supplemental string frame B' is faced to the rear so that the strings E' thereon have to be struck from the rear toward the front. By this arrangement, the set 10 of strings is divided into two sections arranged in different vertical planes facing each other and the complete set of strings will occupy approximately one-half the width of the ordinary set of strings strung 15 in substantially the same vertical plane.

The sounding board D is substantially half the size of the sounding board employed in the ordinary piano or player piano and this is somewhat advantageous, as piano 20 players are apt to be played too loudly and a smaller sounding board produces less volume but can be arranged to keep the tone.

The supplemental sounding board D' for the treble notes being arranged at the front 25 of the piano, allows a very brilliant rendering of the treble section of the strings and the two sounding boards D and D' being separated a considerable distance will not interfere with each other, G—G' designate 30 the set of piano action units. This set of piano action units, as shown, is divided into two sections arranged out of line with each other and substantially within the same width. In the modification under consideration 35 the two sections are arranged in different vertical planes, the rear section G being arranged to strike and operate the bass strings E and the front section G' being arranged to strike and operate the treble 40 strings E'.

H—H' designate a set of operating pneumatics for the piano action units, which set is arranged in two sections, each section being arranged in two rows, the upper section 45 H being arranged to operate the wippines of the rear section G of the action units, and the lower section H' being arranged to operate the wippines of the front section G' of the action units. The arrangement of 50 pneumatics is shown particularly in Fig. 4. The pneumatics are arranged on arms extending out from a secondary valve box I, secured to which is a primary valve box I', this primary valve box being preferably 55 made in two sections as indicated. The upper pneumatics H are connected to levers 20 which carry small springs or flexible fingers set in position to engage the wippines of the section G of the action units, and the lower 60 pneumatics H' are connected to levers 21 which carry springs or flexible fingers set in position to engage the wippines of the other section G' of action units. These 65 levers 21 are inclined downwardly as shown, so as to clear the rear section G of the ac-

tion units, and the lower pneumatics are preferably made to have a longer throw than the upper pneumatics to compensate for the difference in length between the levers 20 and 21 and the different striking points at 70 which they engage their respective wippines, said lower pneumatics being also preferably made shorter than the upper pneumatics so as to have substantially the same cubic capacity. The levers 20 and 21 are preferably 75 made out of metal so as to come in small space and are strung on a shaft 22 or supported by suitable bearings on top of the valve box I. The levers 20 and 21 are provided with upwardly extending arms 23 and 80 a plate 24 is secured to the top of the valve box at the rear thereof and provided with adjusting screws 25 which have soft tips 26 set in position to engage the lever arms 23. By adjusting the screws 25 the upward motion 85 of the levers will be properly limited so that the movable leaves of the pneumatics will not come together and produce disagreeable sounds. By using the springs on the levers a flexible striking action is given 90 to the wippines. A particularly advantageous point in the above construction resides in the fact that the valve boxes, the set of pneumatics, levers, etc., can be made as a unit and can be placed in position in the 95 piano casing very expeditiously and cheaply.

J designates a box or frame secured to the front of the casing A. Two doors K—K' are arranged on the piano casing, which doors are opened when a music roll is to be 100 inserted and the instrument played, and which doors are usually closed when the instrument is not to be played. Arranged within the box J is a tracker L and journaled in the box is a take-up spool M. The 105 usual bearings 10 and 11 are arranged in the box so that a roll of music can be placed in position above the tracker and the usual set of gearing N is arranged at the right of 110 the box, as shown in Fig. 3, so that the perforated note sheet O can be drawn over the tracker L by the take-up spool M or re-wound on the music spool after playing. If desired, an automatic tracking device P can be arranged at the left of the box J 115 to keep the note sheet during its travel automatically in proper position laterally on the tracker. The automatic tracking device can be operated from holes in the 120 tracker in the ordinary way.

Q designates a pneumatic motor, placed in the same width as the tracker, which motor in the construction under consideration, may be arranged below the box J, and which motor is connected by sprocket wheels 125 and a sprocket chain to operate the gearing N.

R—R designate the operating pedals which are pivoted to a frame or bar 12 and which frame is attached to the casing by 130

links 13 pivoted to blocks so that the pedals can be swung up into the casing out of the way when the instrument is not in use, as indicated in dotted lines in Fig. 2.

5 A door S is arranged to slide in the front of the casing to cover or uncover the opening through which the pedals are swung out from and into the piano casing, and suitable operating means may be provided for this door. Each pedal connects by a link 14 with a long link 15 to operate one of a pair of feeders or bellows T—T. Each link 15 is guided and supported by a crank arm 16 pivoted in a support or bracket 17 secured 10 to the bottom of the piano casing. The feeders are arranged on a suitable wind-trunk U connected to which is a storer V. The wind-trunk U connects by means of any of the usual regulators and passages W to the 15 valve boxes and also by means of suitable connections and regulator and valve box X to the motor Q.

A support or ledge Y is arranged at the front of the instrument to carry the operating buttons and levers by which the operation of the instrument is controlled, these operating connections being arranged in any ordinary way to adjust and control the operation of the mechanisms. A cover or fall 20 board Z is arranged in connection with the ledge Y so that the operating levers and buttons can be covered up by swinging the fall board to closed position, as shown in Fig. 2.

25 The tubes coming from the perforations in the tracker L are divided into two sections 18 and 19, the bass section 18 being connected to control the primary valves which control the operation of the upper section H of the pneumatics, and the treble section 19 being connected to control the primary valves which control the operation of the lower section H' of the pneumatics. By these arrangements, a piano player of 30 substantially half width relatively to the set of strings is provided. For illustration, in the usual piano construction, a set of eighty-eight strings is provided and this set in the construction shown will be divided 35 nearly equally between the two string frames, or if the strings E of the bass section are to be over-strung, this proportion may be slightly varied; for illustration, there may be from forty to forty-two strings arranged in the bass section E and from forty-eight to forty-six in the treble section E'. As I use the terms "strings," I mean of course to employ the term in the ordinary sense used in piano practice, no matter 40 whether each string is made up of one, two or three wires.

45 While the operating devices shown are pneumatically actuated, it is to be understood that so far as the broad scope of the invention is concerned, other operating in-

strumentalities may be employed such as electromagnets, revolving cylinders, etc., without departing from the broad scope of my invention, which consists in arranging the strings, action units and operating instrumentalities in a piano player so as to provide an instrument substantially of half width.

50 In Fig. 5 a modification is shown in which the main string frame B and supplemental string frame B' are arranged together midway in the instrument facing toward the front, and the two sections G and G' of the action units and the two sections H and H' of the operating pneumatics are arranged over 55 each other. In this construction the motor Q is arranged on top of the box J, and the wind-trunk U, feeders T—T, and storer V are arranged at the rear of the string frames, the storer V being arranged over the feeders 60 T—T. In the arrangement shown in Fig. 5 a single sounding board D is shown and the bridge or bridges F' coöperating with the treble section E' of the strings is cut away so that the bass section E of the strings can 65 pass through the same.

70 In Fig. 5^a an arrangement of string frames is shown by which both a main sounding board D and a supplemental sounding board D' can be employed.

75 In Fig. 6 a modification is shown in which the sections E and E' of the strings are arranged on two string frames B and B' in the interior of the instrument, said string frames being set back to back. In this arrangement, 80 the sections E and E' of the strings may be made substantially the same; that is, the strings may be arranged alternately on the frames B and B' so that the said frames will be substantially the same in shape. A single 85 sounding board may be employed in this construction, or a double sounding board D—D', as illustrated in Fig. 6^a.

90 In Fig. 7 a further modification is shown which consists in arranging the main string frame B in the interior of the instrument and the supplemental string frame B' at the rear of the instrument, the string frames thus being separated and both string frames being faced toward the front, and the two sections 95 of the action units and the two sections of operating pneumatics are arranged so that the both sections of actions will strike to the rear.

100 Other arrangements may be devised and worked out for practising my invention, the broad scope of which comprehends the production of a player piano of substantially half width relatively to the set of strings employed.

105 The modifications shown in Figs. 5, 5^a, 6, 6^a and 7 are not claimed specifically in this application for patent, as pursuant to a requirement of the Patent Office, I have filed three divisional applications for this pur- 110

pose, which applications were filed February 19, 1912, and bear the Serial Nos. 678,656; 678,657; and 678,658 respectively.

The details and arrangements, therefore, herein referred to and illustrated, may be greatly varied by a skilled mechanic without departing from the scope of my invention as expressed in the claims.

Having thus fully described my invention, what I claim and desire to secure by Letters-Patent is:—

1. An automatic player piano having a set of strings, a set of action units therefor divided into sections arranged out of line with each other and having their ends closely bounded by the same vertical planes transverse to the piano casing, and operating devices therefor.

2. An automatic player piano having a set of strings, a set of action units therefor divided into sections arranged parallelly and having their ends closely bounded by the same vertical planes transverse to the piano casing, and operating devices therefor.

3. An upright automatic player piano having a set of strings arranged in different vertical planes, a set of action units therefor, said action units being divided into sections arranged out of line with each other and having their ends closely bounded by the same vertical planes transverse to the piano casing, and operating devices therefor.

4. An upright automatic player piano having a set of strings arranged in different vertical planes, a set of action units therefor, said actions being divided into sections arranged parallelly and having their ends closely bounded by the same vertical planes transverse to the piano casing, and operating devices therefor.

5. An upright automatic player piano of substantially half width relatively to the number of strings employed, having a set of strings and a set of action units, said strings being arranged substantially in two different vertical planes, and said action units being divided into two sections having their ends closely bounded by the same vertical planes transverse to the piano casing, and operating devices therefor.

6. An upright automatic player piano of substantially half width relatively to the number of strings employed, having a set of strings and a set of action units therefor, said strings being arranged substantially in two different vertical planes, and said action units being divided into two sections parallelly arranged and having their ends closely bounded by the same vertical planes transverse to the piano casing, and operating devices therefor.

7. An upright automatic player piano having a set of strings, and a set of action units and operating pneumatics therefor, said action units and pneumatics being di-

vided into sections arranged out of line with each other and having their ends closely bounded by the same vertical planes transverse to the piano casing.

8. An upright automatic player piano 70 having a set of strings, and a set of action units and operating pneumatics therefor, said action units and pneumatics being divided into sections arranged parallelly and having their ends closely bounded by the 75 same vertical planes transverse to the piano casing.

9. An upright automatic player piano having a set of strings arranged in different vertical planes, and a set of action units and 80 operating pneumatics therefor, said action units and pneumatics being divided into sections arranged out of line with each other and within the same width.

10. An upright automatic player piano 85 having a set of strings arranged in different vertical planes, and a set of action units and operating pneumatics therefor, said action units and pneumatics being divided into sections arranged parallelly and having 90 their ends closely bounded by the same vertical planes transverse to the piano casing.

11. An upright automatic player piano of substantially half width relatively to the 95 number of strings employed, having a set of strings and a set of action units and operating pneumatics therefor, said strings being arranged substantially in two different vertical planes, and said action units and pneumatics being divided into sections having 100 their ends closely bounded by the same vertical planes transverse to the piano casing.

12. An upright automatic player piano of substantially half width relatively to the 105 number of strings employed, having a set of strings and a set of action units and operating pneumatics therefor, said strings being arranged substantially in two different vertical planes, and said action units and pneumatics being divided into two sections 110 parallelly arranged and having their ends closely bounded by the same vertical planes transverse to the piano casing.

13. An upright automatic player piano of 115 substantially half width relatively to the number of strings employed having a set of strings and a set of action units and operating pneumatics, said strings being arranged substantially in two planes, and the action units and operating pneumatics being divided into sections, the units of each section being spaced from each other the usual distance, and valve boxes for said pneumatics.

14. An upright automatic player piano of 120 substantially half width relatively to the 125 number of strings employed having a set of strings and a set of action units and operating pneumatics, said strings being arranged substantially in two planes, and the action units and operating pneumatics being di- 130

- vided into sections, the units of each section being spaced from each other the usual distance, and a wind trunk for said pneumatics.
15. An upright automatic player piano of substantially half width relatively to the number of strings employed having a set of strings and a set of action units and operating pneumatics, said strings being arranged substantially in two planes, and the action units and operating pneumatics being divided into sections, the units of each section being spaced from each other the usual distance, and a valve box and wind trunk for said pneumatics.
- 15 16. An upright automatic player piano of substantially half width relatively to the number of strings employed having a set of strings and a set of action units and operating pneumatics, said strings being arranged substantially in two planes, and said action units and operating pneumatics being divided into sections, the units of each section being spaced from each other the usual distance, a pair of pedals arranged at the front of the instrument and to fold up into the casing, and a pair of feeders arranged at the rear of the pedals.
17. An upright automatic player piano of substantially half width relatively to the number of strings employed having a set of strings and a set of action units and operating pneumatics, said strings being arranged substantially in two planes, and said action units and operating pneumatics being divided into sections, the units of each section being spaced from each other the usual distance, a pair of pedals arranged at the front of the instrument and to fold up into the casing thereof, and a pair of feeders arranged at the rear of the instrument behind the pedals.
18. An upright automatic player piano of substantially half width relatively to the number of strings employed having a set of strings, and a set of action units and operating pneumatics, said strings being arranged substantially in two planes, and said action units and operating pneumatics being divided into sections, the units of each section being spaced from each other the usual distance, a pair of pedals arranged at the front of the instrument so as to fold up into the casing, and a pair of feeders and a storér arranged at the rear of the casing.
- 55 19. An upright automatic player piano of substantially half width relatively to the number of strings employed having a set of strings and a set of action units and operating pneumatics, said strings being arranged substantially in two planes, and said action units and operating pneumatics being divided into sections, the units of each section being spaced from each other the usual distance, a tracker, a sheet manipulating mechanism, a motor, pedals arranged at the
- front of the instrument, and a pair of feeders and a storér arranged at the rear of the instrument.
20. An upright automatic player piano of substantially half width relatively to the number of strings employed having a set of strings and a set of action units and operating pneumatics, said strings being arranged substantially in two planes, and said action units and operating pneumatics being divided into sections, the units of each section being spaced from each other the usual distance, a pair of pedals arranged at the front of the instrument, a pair of feeders at the rear of the instrument, and a valve box for said pneumatics.
21. An upright automatic player piano of substantially half width relatively to the number of strings employed having a set of strings and a set of action units and operating pneumatics, said strings being arranged substantially in two planes, a pair of pedals arranged at the front of the instrument, and a pair of feeders at the rear of the instrument, and a wind trunk connected to said feeders.
22. An upright automatic player piano of substantially half width relatively to the number of strings employed having a set of strings and a set of action units and operating pneumatics, said strings being arranged substantially in two planes, a pair of pedals at the front of the instrument, a pair of feeders at the rear of the instrument, a valve box, and a wind trunk connected to said feeders.
23. An upright automatic player piano of substantially half width relatively to the number of strings employed having a set of strings and a set of action units and operating pneumatics, said strings being arranged substantially in two planes, a pair of pedals arranged at the front of the instrument, a pair of feeders and a storér at the rear of the instrument, a valve box and a wind trunk, connected to said feeders.
24. An upright automatic player piano of substantially half width relatively to the number of strings employed having a set of strings and a set of action units and operating pneumatics, said strings being arranged substantially in two planes, a tracker, a sheet manipulating mechanism, and a motor arranged within the same width as the tracker.
25. An upright automatic player piano of substantially half width relatively to the number of strings employed having a set of strings and a set of action units and operating pneumatics, said strings being arranged substantially in two planes, a tracker, a motor arranged within the same width as the tracker, a sheet manipulating mechanism, and gearing for operating the same arranged at one side of the tracker.

- 6
26. An upright automatic player piano of substantially half width relatively to the number of strings employed having a set of strings and a set of action units and operating pneumatics, said strings being arranged substantially in two planes, a tracker, a motor arranged within the same width as the tracker, and an automatic tracking device arranged at one side of the tracker.
27. An upright automatic player piano of substantially half width relatively to the number of strings employed having a set of strings and a set of action units and operating pneumatics, said strings being arranged substantially in two planes, a tracker, a motor arranged within the same width as the tracker, a sheet manipulating mechanism, gearing for the same at one side of the tracker, and an automatic tracking device at the other side of the tracker.
28. An upright automatic player piano of substantially half width having a set of eighty-eight strings, action units, and operating devices divided into two sections, arranged substantially within the same width.
29. An upright automatic player piano of substantially half width having a set of eighty-eight strings, action units, and operating devices divided into two sections arranged parallelly substantially within the same width.
30. An upright automatic player piano of substantially half width relatively to the number of strings employed having a set of eighty-eight strings, action units, and operating pneumatics therefor divided into two sections, arranged substantially within the same width.
31. In an upright automatic player piano made of substantially half width, a set of strings divided into a longer or bass section and a shorter or treble section, a set of action units divided into sections to coöperate therewith, and operating devices therefor.
32. In an upright automatic player piano, the combination of a string frame arranged to carry the longer or bass part of a set of strings, a separate string frame arranged to carry the shorter or treble part of the strings, a casing within which said frames are housed substantially within the same width, a set of action units divided into sections to coöperate therewith, and operating devices therefor.
33. In an upright automatic player piano, a string frame arranged to carry the longer or bass section of the strings, a shorter string frame arranged to carry the shorter or treble section of the strings, a set of action units divided into sections to coöperate therewith, and operating devices therefor.
34. An upright automatic player piano having a set of strings divided into two sections facing each other, a set of action units divided into sections to coöperate with the said strings, and operating devices therefor.
35. An upright automatic player piano having a set of strings divided into two sections facing each other, a set of action units divided into two sections arranged back to back, and between the two sections of the strings, and operating devices therefor.
36. An upright automatic player piano having a set of strings divided into two sections facing each other, a set of action units divided into two sections parallelly arranged between the sections of the set of strings, and operating devices therefor.
37. An upright automatic player piano having a set of strings divided into two sections facing each other, a set of action units therefor divided into two sections arranged back to back and between the sections of the strings, and operating devices therefor arranged below the action units.
38. An upright automatic player piano having a set of strings divided into two sections facing each other, a sounding board coöperating with each section of the strings, a set of action units divided into sections arranged between the sections of the strings, and operating devices therefor.
39. An upright automatic player piano having a set of strings divided into two sections facing each other, the bass or longer section being at the rear and the treble or shorter section being at the front, a set of action units therefor divided into two sections arranged between the sections of the strings, and operating devices therefor.
40. An upright automatic player piano having a set of strings divided into two sections facing each other, a sounding board for each set of strings, the longer or bass section being at the rear and the shorter or treble section being at the front, a set of action units divided into sections arranged between said strings, and operating devices therefor.
41. An upright automatic player piano having a set of strings divided into two sections facing each other, a set of action units divided into sections and arranged between the sections of the strings, and operating pneumatics for the action units.
42. An upright automatic player piano having a set of strings divided into two sections facing each other, a sounding board for each section, a set of action units divided into two sections and arranged between the two sections of the set of strings, and a set of operating pneumatics therefor arranged in two sections.
43. An upright automatic player piano having a set of strings divided into two sections facing each other, a sounding board for each section, a set of action units divided into two sections and arranged between the two sections of the set of strings, and a set

of operating pneumatics therefor arranged in two sections of two rows each.

44. An upright automatic player piano having a set of strings divided into two sections facing each other, a sounding board for each section, a set of action units divided into two sections and arranged between the two sections of the set of strings, and a valve box carrying a set of pneumatics divided into two sections:

45. An upright automatic player piano having a set of strings divided into two sections facing each other, a sounding board for each section, a set of action units divided into two sections and arranged between the two sections of the set of strings, and a valve box carrying a set of pneumatics therefor divided into two sections of two rows each.

46. An upright automatic player piano having a set of strings divided into two sections facing each other, a sounding board for each section, a set of action units divided into two sections and arranged between the two sections of the set of strings, and a secondary valve box carrying a set of operating pneumatics thereon arranged in two sections.

47. An upright automatic player piano having a set of strings divided into two sections facing each other, a sounding board for each section, a set of action units divided into two sections and arranged between the two sections of the set of strings, and a secondary valve box carrying a set of operating pneumatics therefor arranged in two sections, and a primary valve box connected to the secondary valve box.

48. An upright automatic player piano having a set of strings divided into two sections facing each other, a sounding board for each section, a set of action units divided into two sections and arranged between the two sections of the set of strings, a set of operating pneumatics therefor divided into two sections, and two sets of pivoted striking levers operated by the pneumatics, said levers being arranged to engage the wippets of the two sections of the actions.

49. An upright automatic player piano having a set of strings divided into two sections facing each other, a sounding board for each section, a set of action units divided into two sections and arranged between the two sections of the set of strings, a set of operating pneumatics therefor arranged in two sections, a set of operating levers arranged in two sections, the levers in one section being different in length relatively to the levers in the other section, and flexible fingers carried by the levers.

50. An upright automatic player piano having a set of strings divided into two sections facing each other, a sounding board for each section, a set of action units divided into two sections and arranged between the

two sections of the set of strings, a set of operating pneumatics therefor divided into two sections, a set of striking levers divided into two sections, the levers in one section being different in length relatively to the levers in the other section, and means for limiting the movement of the levers.

51. A pneumatic apparatus for a half width player piano comprising a valve box, a set of pneumatics divided into two sections connected thereto, and a set of levers pivoted thereon and connected to the operating pneumatics, said levers being arranged in two sections, the levers in one section being different in length relatively to the levers in the other section.

52. A pneumatic apparatus for a half width player piano comprising a valve box, a set of pneumatics attached thereto and divided into two sections, a set of levers pivoted thereto and connected to the pneumatics in two sections, the levers in one section being different in length relatively to the levers in the other section, and flexible fingers carried by the levers.

53. A pneumatic apparatus for a half width player piano comprising a valve box, a set of pneumatics connected thereto and arranged in two sections, one section having a greater movement than the other, and a set of pivoted levers divided into sections, the levers in said sections being of different shape.

54. A pneumatic apparatus for a half width player piano comprising a secondary valve box, a primary valve box attached thereto, a set of operating pneumatics attached to the secondary valve box and arranged in two sections, the pneumatics of one section having a greater movement than the pneumatics of the other section, and operating levers pivoted to the secondary valve box, said levers being divided into two sections the levers in one section being different in length relatively to the levers in the other section.

55. A pneumatic apparatus for a half width player piano comprising a secondary valve box, a set of pneumatics attached thereto and arranged in two sections of two rows each, one section having a greater throw than the other, a set of levers pivoted to the secondary valve box and divided into two sections, the levers in one section being different in length relatively to the levers in the other section, and a primary valve box secured to the secondary valve box.

56. A pneumatic apparatus for a half width player piano comprising a secondary valve box, a set of pneumatics attached thereto and arranged in two sections of two rows each, one section having a greater throw than the other, a set of levers pivoted to the secondary valve box and divided into two sections, the levers in one section being

different in length relatively to the levers in the other section, and flexible striking fingers carried by said levers.

57. A pneumatic apparatus for a half width player piano comprising a secondary valve box, a set of pneumatics attached thereto and arranged in two sections of two rows each, one section having a greater throw than the other, a set of levers pivoted to the secondary valve box and divided into two sections, the levers in one section being different in length relatively to the levers in the other section, and means for limiting the movements of the levers.

58. A pneumatic apparatus for a half width player piano comprising a secondary valve box, a set of pneumatics attached thereto and arranged in two sections of two rows each, one section having a greater throw than the other, a set of levers pivoted to the secondary valve box and divided into two sections, the levers in one section being different in length relatively to the levers in the other section, flexible striking means carried by said levers, means for limiting the movement of the same, and a primary valve box carried by the secondary valve box.

59. An upright automatic player piano having a set of strings divided into two sections facing each other, a set of action units divided into two sections arranged back to back and between said strings, a set of operating pneumatics for said action units, and a pair of feeders and a storer arranged below the pneumatics.

60. An upright automatic player piano having a set of strings divided into two sections facing each other, a set of action units divided into two sections arranged back to back and between said strings, a set of operating pneumatics for said action units, a

pair of feeders and a storer arranged below the set of pneumatics, and a pair of pedals arranged in front of the feeders and storer.

61. An upright automatic player piano 45 having a set of strings divided into two sections facing each other, a set of action units divided into two sections arranged back to back and between said strings, a set of operating pneumatics for said action units, a 50 pair of feeders arranged below the pneumatics, and a pair of folding pedals arranged in front of the feeders and storer.

62. An upright automatic player piano 55 having a set of strings divided into two sections facing each other, a set of action units divided into two sections arranged back to back and between said strings, a set of operating pneumatics for said action units, a 60 pair of feeders and a storer arranged below the set of pneumatics, a tracker and note sheet manipulating mechanism arranged at the front of the piano, and connections therefrom to the set of pneumatics.

63. An upright automatic player piano 65 having a set of strings divided into two sections facing each other, a set of action units divided into two sections arranged back to back and between said strings, a set of operating pneumatics for said action units, a 70 tracker and note sheet manipulating mechanism arranged at the front of the instrument, and a pneumatic motor therefor arranged below the tracker.

In testimony whereof I have hereunto set 75 my hand, in the presence of two subscribing witnesses.

LOUIS W. SOUTHGATE.
